UNITED STATES PATENT OFFICE.

THOMAS E. CLARK, OF DETROIT, MICHIGAN, ASSIGNOR TO CONTINUOUS TRAIN CONTROL CORPORATION, OF DETROIT, MICHIGAN, A CORPORATION OF MICHIGAN.

TRAIN-CONTROL APPARATUS.

Application filed November 21, 1923. Serial No. 676,014.

This invention relates to automatic apparatus designed to control the operation of railway trains, and its object is to provide means for announcing to the engineer of one train that the next or the second block in advance is occupied by another train and for positively compelling the speed of the train to be reduced according to the condition of the two blocks in advance.

10 This invention consists, in combination with a railway track divided into blocks, of a generator of radio-frequency current for each block, electric circuits connecting the generator to the rails of the block, and a three-position relay controlled by alternating current in the rails of the next block in advance for determining by its position when energized the frequency and wave length of the current transmitted to its block 20 for the purpose of indicating clear, danger or caution indications in the vehicles occupying said block.

It further consists in means for supplying an alternating current to the rails of each block and a device for controlling the direction of the current, said device being governed by the three-position relay of the block in advance which therefore determines the radio frequency current of its own block 30 and the position of the relay of the next block in the rear and the clear, caution or danger indications in said block.

It further consists in providing condensers in the circuits between the radio-frequency generator and the rails to prevent to a great degree the passage of the alternating current from the rails to said generator.

It also consists in a normally energized brake control device in a vehicle, a plurality of circuits each adapted to maintain said device energized, means for opening and closing said circuits according as the vehicle exceeds or lacks a predetermined speed for each of said circuits, a receiving circuit on the vehicle embodying selecting devices for differentiating between the currents of different wave lengths and frequencies, and a radio-frequency relay controlled by said currents for selecting the circuits to the 40 brake-control device.

It also consists in a three-position relay on the vehicle adapted to respond to the positions of the three-position relay at the track side and signals controlled thereby to

indicate clear, caution or danger conditions 55 of the block of track in advance.

It also consists in the details of construction illustrated in the accompanying drawings and particularly pointed out in the claims.

In the accompanying drawings Fig. 1 is a portion of a diagram of the track and vehicle units of this novel train control apparatus. Fig. 1^a is the remaining portion of this diagram. Fig. 2 is a view illustrating a speed governor. Fig. 3 is a view showing a switch operating connection.

Similar reference characters refer to like parts throughout the several views.

The purpose of this train-control system 70 is to provide means which will normally permit the engineer to handle his train without interference so long as he does so properly within certain predetermined limits, 75 obeying the signals along the track or within his cab, but which will apply the brakes if the engineer fails to obey said signals, bringing the train down to the speed which is permitted under the conditions indicated by the signals. Three particular features are 80 of importance.

1. The electrical energy for controlling the train equipment is transmitted from the track rails without the necessity of mechanical contacts. It is therefore not hindered by ice or snow on the rails.

2. The train equipment is under constant control and the controlling energy for the brakes and signals is transmitted constantly from the rails at every point of the track.

3. The track circuit and the locomotive circuit are both closed. If either is opened or is de-energized the locomotive immediately must reduce its speed to correspond to danger conditions.

The installation shown in the drawings is adapted for the operation of trains in one direction only, that indicated by the arrow, as for one track of a double track railway.

Figs. 1 and 1^a show two line wires 1 and 2 which extend from a source of alternating current along the track which is divided by means of the usual insulation into blocks A to H inclusive. Block A is not shown but is supposed to be occupied. The rails are numbered 3 and 4. Connected to the rails of each block by means of the wires 5 and 6 are the track relays 7^c, 7^b, 7^a, 7^c and 7^d, 100 105

each of which predetermines the currents in one of the blocks and is controlled by a current in the block in advance. These relays may be of the standard A. C. type used in block signalling.

Each block receives alternating current and radio-frequency current. The direction of the alternating current in each block is controlled by the track relay of that block which also controls the frequency, wave length and direction of the radio frequency current. This statement as to "direction" of radio-frequency current is made in view of the observed indications that there is a directional effort in radio-frequency currents.

In the drawings I have indicated axles 8 to represent vehicles or trains occupying blocks C, D and G. Block A is also understood to be occupied. Blocks B, E, F and H are unoccupied and the positions of the instrumentalities on the vehicles in blocks C, D and G are respectively for caution, danger and clear conditions. Attention is called to the track instrumentalities of block G. Blocks F and E are unoccupied so that the indications for block G are for clear conditions and for maximum permitted speeds. The track instrumentalities for block F are not shown but are in the same position as those of block C to which reference is made to trace the current passing to the relay 7^g.

An alternating current transformer T C has a primary winding 10 connected to the line wires 1 and 2 by means of the wires 11 and 12. The secondary winding 13 of this transformer connects to the armatures 14 and 15 by means of the wires 16 and 17. The contacts 18, 19 and 20 connect to the rails of block C by means of wires 21, 22, 23 and 24; adjustable choke coils 25 and 26 are provided to keep the radio-frequency current in the rails from passing to the transformer T C. So long as the block B is unoccupied, current will pass to the relay 7^g and hold the armatures 14 and 15 against the contacts 18 and 19+current conditions then occurring in rail 3. Alternating current being used, as in the usual standard three-position signaling track circuits, there is no real positive or negative current, as these words are properly applicable to direct currents only. But in installations of this character, there is relative instantaneous polarity at the time the relays are energized and the result is comparable to the effect of change of direction of direct current. The symbols + and - are therefore used to indicate this relative instantaneous polarity condition. When the block in advance is occupied, as is block C, the relay of the next block in the rear (7^p) is de-energized and - current conditions occur in rail 3 of that block. Therefore-current conditions occur in rail 3 of all blocks immediately in the

rear of all occupied blocks and + current conditions in all other blocks.

When + current condition occurs in rail 3 similar current also passes over wire 5 to the three position track relay, giving that a positive energization, unless the block which receives such current is occupied, in which case no current passes to the relay, it being short circuited by the occupying vehicle. Block F however is not occupied so relay 7^g and its armatures are in + or clear positions. Adjacent each block is a high-frequency rotary transformer or generator 28, connected to the line wires 1 and 2 by the wires 29 and 30 and to the primary winding 32 of the radio-frequency transformer R by the wire 33, armature 34, contact 35, wire 36, armature 37, contact 38 and wire 39. It also connects to this winding 32 by the wire 40. An adjustable contact 42, wire 43, and contact 44 are also provided as will be pointed out farther on. Condensers 45 are provided in the wires 33 and 40.

The secondary winding 48 of the radio-frequency transformer R connects to a switch S by means of wires 49 and 50, condensers 45 being connected into these circuits. The switch connects to the rails 3 and 4 by means of wires 52 and 53, an adjustable resistance 54 being connected into the wire 52 and an adjustable inductance 55 into the wire 53. The condensers 45 are constructed to permit the passage of the high frequency current which is used for controlling the train installation and prevent the short circuiting of the A. C. current of the track circuit as they prevent the passage of enough of the alternating current conducted to the rails by the wires 21 and 23 to materially affect the operation of the relay 7 of that block.

These condensers are well known and are produced to materially block all alternating currents of lower frequencies than those which they are constructed to pass.

Blocks E and F being unoccupied, the radio-frequency current for block G is produced by current from the generator 28 passing over the wire 33, armature 34, contact 35, wire 36, armature 37, contact 38, wire 39, and the entire length of the primary winding 32 of the transformer R G. The resultant current in the secondary winding 48 is of comparatively low frequency and long wave length and I have marked the wire 52 with + to indicate a directional effort. When the block (G) is occupied by an axle 8, a closed oscillating circuit is produced which has a powerful inductive effect just adjacent the axle 8 and greatest apparently on the side of the axle toward the points of connection of the wires 52 and 53.

As blocks C, D and G are occupied, the track relays 7 controlling the installations for the blocks next in the rear are short cir-

cuated and the armatures 34 of these relays break engagement with the contacts 35, thus opening the circuits to the primary windings of the transformers whose secondary windings are connected to the rails of blocks D, E and H respectively. No radio-frequency current therefore passes to the rails of a block at whose exit end there is an unenergized relay 7 connected to the occupied rails of the next block in advance.

In order to cause the members of each switch S to swing with an armature 37, a link 110 may be connected to the switch members by means of pins 111, and the link 15 may be formed with a slot 112 to receive the pin 113 on the armature 37. The armature may swing from either of its "polar" positions to neutral without disturbing the switch, but when it swings from neutral to either of its "polar" positions, the switch 20 must swing with it unless the armature happens to swing back to its last polar position.

Where the block in advance is occupied, as is the case with respect to block B, the alternating track current passing from rail 3 of block B to relay 7^c has relative instantaneous negative polarity so that the relay will indicate negative energization and swing the armature 37 to engage the contact 44. The 25 current from the generator 28 then passes over the wire 33, armature 34, contact 35, wire 36, armature 37, contact 44, wire 43, contact 42 and over only a portion of the primary winding 32 of the transformer R C. 30 The induced radio-frequency current in the secondary winding 48 is of greater frequency and lesser wave length than in that of block G. Each armature 37 may have a connection with the switch S of the same block so that 35 when the armature is swung from central position it moves the switch with it. The secondary or radio-frequency current then passes over the wire 50 to the switch S, adjustable inductance 55 and wire 53 to rail 40 4, thus producing an induced circuit between the rails having an opposite directional effort to that formed in block G. This may be termed a caution condition of current, that of block G being termed a clear condition although these relations are not fixed, but may be interchanged if desired, depending entirely on the adjustment and connections of the instrumentalities on the vehicle or train being controlled.

45 On the vehicle is a three-position relay P of the type shown in my pending application Ser. No. 335,941 filed Nov. 5, 1919, with four vanes and four coils so that the vanes may be turned in either direction from central position. This instrument is indicated diagrammatically to consist of a shaft 60 on which the vanes 61, 61^a, 62 and 62^a are mounted. To this shaft are connected the arms 63 and 64, the former adapted to engage the 50 contacts 65, 66 and 67 which are connected to

the lamps 68, 69 and 70 by the wires 71, 72 and 73 respectively. These wires connect to a current source such as a battery 75 by means of a wire 76. The shaft 60 connects to the current source by a wire 74. In Fig. 2 70 I have diagrammatically shown a speed governor comprising a shaft 80, a driving pulley 81 thereon so that it may be rotated by an axle of the vehicle, weights 82 connected to the pulley 81 and a collar 83 by the links 84, and a cross bar 85 movable up and down by the links 84. A wire 86 connects to this cross bar. Three contact plates 87, 88 and 89 of metal of varying lengths connect to insulating members and the bar 85 carries brushes 90, 91 and 92^a. Wires 93, 94 and 95 connect these plates to the contacts 96, 97 and 98 adapted to be engaged by the arm 64. The wire 86 connects to one end of the winding of an electro-magnetic valve V, the other end of the winding being connected to the current source 75 by a wire 99. The valve V is normally open but is closed by the electro-magnet when that is energized.

When there is no radio-frequency current in the track rails of the block occupied by the vehicle, as the block D, no current passes to the relay P D and the arms 63 and 64 engage the central contacts 66 and 98 respectively. Current passes from the current source 75 to the danger lamp 69 and to the contact plate 89. If the vehicle is moving at more than the speed predetermined for danger conditions, say four miles per hour, the brush 92^a will be lifted above the metal portion of the contact plate 89 and the circuit from the source 75 through the valve V will be broken, the valve opening to permit application of the brakes which will check the speed of the vehicle until it is no greater than that predetermined for danger conditions.

When the caution conditions are present in the track instrumentalities, as in block C, the relay P C closes the circuits to the caution lamp 68 and the middle plate 88. The circuit to the train valve V is kept closed until the train speed exceeds that which is predetermined for caution conditions, say fifteen miles per hour, at which point the circuit 110 between the current source and the valve is opened to cause the application of the brakes.

When clear conditions are present in the track instrumentalities, as shown in block G, the relay P G closes the circuit to the clear lamp 70 and to the plate 87. The circuit to the train valve V is kept closed until the vehicle exceeds the highest permissible speed for that vehicle, at which point the brush 90 moves from contact with the plate 87 and 120 opens the circuit to the valve V. The lamps 68, 69 and 70 therefore indicate to the operator, whether engineer or motor man, the condition of the track ahead and the speed 125 permitted for the block being occupied and 130

these indications will be changed at any time the conditions of the track in advance are changed.

As stated before, radio-frequency currents are usually present in the rails of the track occupied by the vehicle being controlled by the present system. In order to receive the induced current in the zone adjacent the connection between the rails two inductor loops 101 and 102 are mounted on the vehicle and preferably about six inches from the rails. Conductor wires 103 and 104 lead to the adjustable tuner coils 105—106 and 107—108, the connection between the windings 105 and 107 being grounded to obtain clearness of the oscillating currents. The tuner coil 105—106 is adjusted for clear conditions while the coil 107—108 is adjusted for caution conditions. Induced current in the conductor 104 and coil 105 induces current in the coil 106 in the adjustable inductance 109, in the repulsion coils 110 and 111 and in the adjustable resistance 112. The energized repulsion coils 110 and 111 act on the vanes 61 and 61^a and turn the shaft 60 clockwise as shown in Fig. 1^a. As stated before, the inductance 54 and resistance 55 of the track installation serve to split the phase of the waves of the radio-frequency track current, and this condition is intensified by the inductance 109 and resistance 112 at the ends of the coil 106. In the same manner, the caution current has no effect on the coils 106 but the tuner coil 107—108 receive this high frequency, short wave length radio-frequency current and the phase displacement is intensified by the adjustable inductance 114 and resistance 115 so that the action of the repulsion coils 116 and 117 will have a powerful effect on the vanes 62 and 62^a, sufficient to swing the arms 63 and 64 to the positions shown by P C at the right in Fig. 1.

The construction of the three position rotary relay P is similar to that shown by the Thomas E. Clark applications, Ser. No. 335,941, filed November 5, 1919, and may be the same as that shown in the Thomas E. Clark application Ser. No. 27,589, filed May 50, 1925.

I claim:

1. In an apparatus for controlling the movement of railway trains, the combination of a railway track divided into blocks, a radio frequency generator for each block, an electro-magnetic controller therefor whereby the frequency and wave lengths of the radio frequency current may be varied, conductors between said generator and the rails of the track of its block, a second generator for each block to provide other current therefor, and electric circuits between the rails of said block and the electro-magnetic controller of the next adjacent block to the rear according to direction of the traffic whereby the opera-

tion of the controller of the next adjacent block in the rear may be determined.

2. In an apparatus for controlling the movement of railway trains, the combination of a railway track divided into blocks, a generator for radio frequency current for each block, electric circuits between the generator and the rails of the track, an electro-magnetic controller adjacent each generator whereby the frequency and wave lengths of the radio frequency current may be varied, and electric circuits between said controllers and the rails of the block in advance whereby the actions of the controller may be governed.

3. In an apparatus for controlling the movement of railway trains, the combination of a railway track divided into blocks, a current source for each block and connections between the current source and the rails of the block, a relay controlling said connections to determine the character of current passing to its block, a generator for radio frequency current for each block, electric connectors between the generator and the rails of its block, means controlled by the relay of each block for determining the wave length and frequency transmitted by each generator, and electric circuits between the relay and the rails of the block in advance.

4. In an apparatus for controlling the movement of railway trains, the combination of a railway track divided into blocks, a three-position relay for each block, electric circuits between the relay and the rails of the block in advance, a source of oscillating current for each block, electric connectors between said source and the rails of the block, means controlled by each relay for determining the direction of said current to the rails of the next block to the rear, a radio frequency current generator and transformer for each block, electric circuits connecting the generator and the rails of its block, and means controlled by the relay of the next block in advance when energized for determining the wave lengths and frequency of the radio frequency current in the rails of the block to which said generator is connected.

5. In an apparatus for controlling the movements of railway trains, the combination of a railway track divided into blocks, a source of alternating current for each block and electric connectors between said source and its block, a three-position relay to control the direction of the alternating current in the rails of said block, electric circuits between the relay and the rails of the block in advance so that the armature position of each relay is determined by the character of alternating current in the rails of the block in advance, a generator and transformer of radio frequency current for each block and electric circuits connecting said generator to

the rails thereof, and means controlled by the position of an armature of the relay of said block to determine the frequency and wave lengths of the radio frequency current passing to said rails of said block.

6. In an apparatus for controlling the movements of railway trains, the combination of a railway track divided into blocks, a three-position relay for each block, electric circuits between the relay and the rails of the block in advance, a source of oscillating current for each block, electric connectors between said source and the rails of the block and embodying inductance coils, means controlled by the relay for determining the direction of said current to the rails of the next block in the rear of the block to which said relay is connected, a radio frequency current generator for each block, electric circuits and a transformer connecting the generator and the rails of its block, condensers between the generator and transformer and between the transformer and track rails and means controlled by each relay when energized for determining the wave lengths and frequency of the radio frequency current in the rails of the next block in the rear of the block to which said relay is connected.

7. In an apparatus for controlling the movements of railway trains, the combination of a track divided into blocks, means for transmitting radio frequency currents of predetermined frequencies and wave lengths to the rails of each block, and controlled as to frequency and wave length by the occupancy of the first and second blocks in advance, of a three-position relay mounted on a vehicle and controlled by the frequency and wave length of the current in the rails occupied by the vehicle for automatically enforcing correspondingly varying limitations on the speed of said vehicle.

8. In an apparatus for controlling the movement of railway trains, an electrically governed air brake valve, a source of electric current for normally energizing said valve to hold it closed, three circuits between the current source and valve, means controlled by the speed of the vehicle, for opening and closing said circuits according as the vehicle exceeds or lacks a predetermined speed for each circuit, and means controlled by the wave length of radio frequency currents in the track for selecting one or another of said circuits and thereby the maximum speed of the vehicle during the condition under which said selection was made, said means embodying a three-position radio-frequency relay and inductance coils and resistance coils for selecting the currents to operate same.

9. In an apparatus for controlling the speed of railway trains, the combination with a changeable element on a vehicle having a tendency to assume an extreme condition, of automatic means on the vehicle controlled by said element for imposing varying restrictions on the speed of the vehicle, the restricted speeds for the vehicle established by said means being progressively decreased as said element changes toward its extreme condition, a radio frequency current generator adjacent the track and electric circuits connecting it to the rails of the track, automatic means responsive to the presence of a train on the track for controlling the wave lengths and frequency of the current transmitted by said generator, a receiving circuit on the vehicle to receive current induced by said current in said rails, and a radio frequency relay in said receiving circuit to govern the position of said changeable element on the vehicle.

THOMAS E. CLARK.
